[57] CLAIM

The ornamental design for a fluorescent lamp, as shown and described.

DESCRIPTION

FIG. 1 is a top, front and right side perspective view of a fluorescent lamp showing my new design;
FIG. 2 is a front elevational view thereof, a rear elevational view being identical to the front;
FIG. 3 is a top plan view thereof;
FIG. 4 is a bottom plan view thereof;
FIG. 5 is a right side elevational view thereof, a left side elevational view being identical to the right; and,
FIG. 6 is a cross-sectional view thereof taken on line 6—6 in FIG. 2.

FIG. 1

FIG. 2

FIG. 3

FIG. 4

FIG.5

FIG.6
